APPARATUS FOR RE-REFINING
LUBRICATING OIL

Myran J. Livingston, Pelham, N. Y.

Application August 4, 1944, Serial No. 548,114

5 Claims. (Cl. 196—16)

1

This invention relates to a process and apparatus for contact filtration of oil, particularly for the purification of lubricating oil. My process and apparatus find a particularly useful application to the re-refining of used lubricating oil of petroleum origin. Such used oil may constitute the steam engine lubricants, drainings from crank cases of gasoline, gas, or Diesel engines, used turbine oils, and engine and other lubricating oils used in lubrication of machinery.

It is now well established that lubricating oil which has deteriorated in use to such an extent that its replacement by refined oil is economically advantageous may be, if properly re-refined, placed in a condition such as to make it again useful as a lubricating oil. In fact, I have found when such an oil is re-refined according to my process and when employing my apparatus not only does the oil have as good properties as the original oil when subjected to all the conventional tests, but in many of its properties, particularly in its resistance to oxidation, it is improved in quality.

This improvement in lubricating oil properties I believe to be the result of deep-seated and important changes in the chemical constitution of the oil resulting from a controlled oxidation of the "used" oil in the presence of an active adsorbent and catalyst. "Used" lubricating oil, especially oil drained from the crank cases and sumps of internal combustion engines, such as the gasoline engine, gas engine, and Diesel or semi-Diesel engines, here included under the term "used lubricating oil," has been subjected to relatively high temperatures under oxidizing conditions. Such oils contain, in addition to sludge, partially oxidized and partially polymerized compounds which are themselves reactive, and on continued use will oxidize, polymerize, and resinify. These materials also have a catalytic effect in that they promote the resinification and oxidation of the oil. The process, as is well known, is "auto-catalytic." The exact composition of these oxidized fractions which impart this instability and "auto-catalysis" is not known to petroleum scientists, but the latest theory supported by the most facts is that they are organic peroxides formed by the oxidation of oil. The process of controlled pre-oxidation in the presence of a catalytic adsorbent causes an oxidation of the unstable and catalytic components of the oil fraction and their immediate removal from the zone of oxidation by adsorption on the solid adsorbent. The peroxides and other intermediate compounds forming part of the chain reaction of oxidation

2

are removed from the oil by adsorption. By this process of adsorption, the unstable and unstabilizing components are removed by adsorption or oxidized and removed by adsorption, thus preventing the re-accumulation of peroxides or other catalytic materials in the oil which thereafter, on continued use, again unstabilize the oil.

Parallel to this process stabilization of the oil by pre-oxidation in the presence of catalytic adsorbent, the adsorbent also exhibits its normal adsorptive capacities to remove color bodies, sludge, carbon, moisture, unsaturated and unstable bodies not converted by the oxidation process.

15 The purified oil after subjection to blowing with air at elevated temperatures in the presence of solid adsorbent having catalytic properties, herein referred to as the pre-oxidation process, is then cooled in an inert atmosphere until it is below 20 an active oxidation temperature and then separated from the adsorbent.

I believe this step to be important, in that oxidation, in the absence of an adsorbent which would have the property of removing the products of oxidation, would leave in the oil peroxides, acids, and other oxidation catalysts to unstabilize the oil. By cooling the clay and oil mixture to below an active-oxidation temperature and permitting a partial separation of the clay, I may 30 then use air pressure as a convenient means of pressure filtration without incurring the danger of unstabilization by oxidation.

While my process is applicable to and may be employed in many forms of apparatus, the apparatus hereinafter described is in such simple and convenient form as to make my process available and economical for use in garages, oil service stations, and even for operators of but a small number of cars, buses, or automobiles.

40 Such a need has been long felt but no apparatus sufficiently economical to make it available to the small operator is available. This device, therefore, it is believed, fills a long-felt and long-unsatisfied need.

45 In principle, my apparatus provides a simple mechanism for flowing air through the heated oil to which the adsorbent has been added. The air causes a pre-oxidation of the oil as described above. It also has the advantage of keeping the oil and adsorbent well mixed during the treatment. This avoids moving parts to agitate the oil and adsorbent at the elevated treating temperature. The air, therefore, has a twofold function. The adsorbent decolorizes and purifies the

3

oil and removes unstable components, and may also aid the oxidation process catalytically.

The air stream, aided, if desired, by vacuum maintained on the oil, also removes diluent and odoriferous fractions. The vapors are condensed and the unvaporized and odoriferous fractions disposed of, as will be later described.

The oil is then steamed and the air and residual vaporous and odoriferous components removed and condensed.

The uncondensed vapors from both stages, i. e., steaming and air blowing, are disposed of by intermingling with water in the water jet which maintains a suction of the condenser and treater.

The oil and adsorbent are then transferred from the contactor into a cooling chamber by steam pressure in the absence of air and cooled while out of contact with air. It will be seen that all machinery for transferring, agitating, and filtering the oil is made by steam or air pressure. The adsorbent is then removed from the cooled oil by filtration, using air pressure.

This invention will be further described by reference to the accompanying drawings which illustrate a preferred embodiment of my invention. In the drawings:

Fig. 1 is an assembly view of my apparatus taken in part vertical section along the line 1—1 of Fig. 2;

Fig. 2 is a plan view shown in part section taken along the line 2—2 of Fig. 1;

Fig. 3 is another section taken 90° to the section of Fig. 1 in the direction of arrow 3 on Fig. 1;

Fig. 4 is a detail of the heater employed in the contactor-reactor;

Fig. 5 is a fragmentary detail of the filter;

Fig. 6 is a fragmentary detail of the bottom of the filter of Fig. 5;

Fig. 7 is a diagrammatic flow sheet illustrating the apparatus and its use; and

Fig. 8 is a cross section of a suitable container for the treating agent for use in a modification of my invention.

The treating chamber 1 is preferably formed of a flat-bottomed and flat-topped cylindrical vessel. The choice of such a vessel permits of an economical construction for a cost far less than would be entailed in employing vessels with bumped heads and cone bottoms. In order, however, to obtain the benefits of a cone bottom, permitting a complete transference of material and also efficient agitation and mixing of oil and adsorbent, I have employed the expedient of mounting this treating vessel so that its axis is inclined, for example, at approximately 45° to a horizontal plane, as will be described below. Vessel 1, hereinafter referred to as a contactor, is formed with a bottom 2 set at some short distance from the end of the wall of the vessel 1 to give a cylindrical flange 8 to house the electrical resistor heater 10 to be described below. A spout 4, whose axis is set about 45° to the axis of treater 1, carries a cap 5 accessible from the exterior of the enclosing cabinet 19. The contactor 1 is surrounded by insulation 6 and enclosed with a metal housing 7.

The electrical heater 10, referred to above, shown in Fig. 4, is mounted underneath the bottom 2 by means of clips and bolts 11. Such resistors are well known and may be purchased in the open market. They are particularly useful for use in my type of apparatus and are superior for my purpose to immersion type of heaters, since they avoid the necessity of providing fittings which will pass through the walls of the treater.

4

They are also lower in price than the immersion type heater. An additional advantage is the simplicity of installation and removal. The insulation may be made sectional to fit over the fittings of the vessel. A bottom portion may also be provided suitably attached to the enclosing metal wall 7. By removing the bottom portion, the heater is accessible and may be installed or removed.

Passing through the walls 7 and 1 is a thermometer well 12, closed at the bottom, to provide a means for measuring the temperature of the oil in contactor 1. A thermostat 13 is passed through the walls of 7 and 1 and securely mounted in an airtight and leak-tight fitting.

As illustrated in Figs. 1, 2, and 3 the contactor 1 is mounted in its inclined position by means of clips 14 and 15 positioned on angles 16, 17, and 18 mounted on the walls of the enclosing cabinet 19. This cabinet surrounds the entire apparatus and gives a neat appearance to the device.

Steam generator 20 carried by the top of the housing 19 is covered by a closure 21 carrying a clamp fitting 22. Closure 21 may be held by clamp 22 by means of a spring so that it may act as a pop valve to become unseated and relieve pressure if the steam pressure in 20 becomes excessive. The closure is accessible from the top of the cabinet as illustrated in Fig. 1. Beneath the bottom of the steam generator 20 is positioned a resistor heater 23 similar in character to 10. A pipe 24 is connected near the top of generator 20 and passes through the walls 7 and 1 to connect with a pipe 25 lying on the bottom of the contactor 1. Pipe 25 terminates near the lowest portion of contactor 1, as is shown in Fig. 1. It may be in the form of a spider, permitting discharge of air or steam at various points across the bottom 2, as well as the lowest point in the contactor 1. This will assist in thorough agitation and oxidation and purging by improving the contact of air or steam with all portions of the oil and treating agent. A pipe 21 is connected near or at the uppermost point of the inclined contactor 1. A pipe 28 passing through the wall 7 and the top 3 of the contactor 1 terminates in the lower point of the inclined contactor. A drain line 9 closed by a cap is mounted at this point, as shown in Fig. 1.

This construction permits of the discharge of the contents of the contactor 1 through line 28, as will be explained hereinafter, and through drain line 9 in the same manner as if the contactor had been positioned vertically and a more expensive cone bottom provided. This expedient permits of a material saving in the cost of construction of the apparatus.

The pipe 27 communicates with a condenser 30 through valve 29. As shown in Figs. 2 and 3, 60 the valve stem of valve 29 is elongated and the wheel 29' of the valve is mounted above the top of the housing 19 and is accessible at that point. The condensate accumulator 30 is covered by a top 31 held securely with a gas-tight closure by means of a bolt 32 screwed into a bracket 33. A valved spout 34' is connected to the bottom of the accumulator 30 and passes through the wall of the housing 19.

This accumulator carries a condenser coil to 70 which water for cooling purposes is passed through pipe 34 controlled by valve 35. The valve stem and wheel 35' is accessible from the top of cabinet 19, as shown in Figs. 1, 2, and 3. The cooling water from the condenser coil discharges through pipe 36 which is in turn connected to 75

the cooling coil 44 in cooler 41. A vent pipe 37 is connected to the upper portion of the accumulator 30 and this vent line carries a sight-glass 38 and also a valve 39, whose valve stem and wheel 39' are accessible from the exterior of housing 19. A cross 40a, which carries a pressure gauge 40', is mounted exterior of the housing 19 and is connected by line 40b to the upper portion of the cooler 41, as will be described later. Pipe 37 also carries a check valve 43. Connected to the upper portion of the accumulator 30 is a pipe 48 which is connected to the ejector 46. The ejector is connected to the coil 44 in the cooler 41. The discharge from 46 enters spout 47 which, if desired, may be connected to 46 by a gas-tight fitting. The spout 47 may be connected to the sewer.

The cooler 41 is formed of a cylindrical vessel with a flat top and flat bottom. It is mounted at an angle, for example, a 45° angle, on clips 52" and 53" on brackets 53' and 52' positioned on the walls of the housing 19. As described in connection with contactor 1, this expedient gives to the flat-bottomed vessel 41 the advantages of a cone bottom. To the upper portion of the container 41 is connected pipe 42 which is in turn connected through valve 43 with the pipe 28 previously described. The valve 43 has a valve stem 43' projecting from the top of the housing 19 and is accessible at that point. To the lowest portion of 41 in its inclined position is connected a pipe 49 which in turn is connected to the housing of the filter 51 through valve 50. The bottom of the filter shell 51 is closed by a perforated closure 54 which carries a screen 53 and a filter 52. This filter may be filter paper, filter cloth, blotting paper, canvas, or other type of filter diaphragms. The filter is preferably some paper such as blotting paper which can act as a gasket to seal the closure at the wall of the shell 51. The perforated closure 54 is held tightly against the shell 51 by means of a swinging clamp 55 and a bolt 56.

The apparatus previously discussed is schematically illustrated in Fig. 7, which also shows the wiring diagram for the unit. A power line 57 is connected to the heater 23 through a switch 59. The heater 10 is connected to line 57 through switch 58 in series with the thermostat 13 and light 64. When the temperature is below the predetermined upper limit at which the thermostat is set to open the current, the light is on. When the temperature rises above the safe upper limit, the thermostat breaks the circuit and the light goes out. A visual warning is thus available.

The operation of this device and the application of my process for the re-refining of used lubricating oil are illustrated by the diagrammatic flow sheet of Fig. 7 taken together with the description of the apparatus previously given.

The cap 21 is removed. Water is introduced into the container 20 to a level below the outlet pipe 24. The cap 5 is removed and valve 50 is closed. The used oil to be re-refined is poured into the contactor 1 to leave a vapor space above the level of the oil. The treating agent is then introduced through the spout 4.

The treating agent may be any useful type of adsorbent such as an adsorbent synthetic magnesium silicate, natural decolorizing clays, such as natural magnesium silicate clays, acid treated montmorillonite clay, such as the acid activated bentonite clays, Activated Alumina, or activated adsorbent carbon. I prefer, however, to employ adsorbents which are also catalytically active in promoting the treatment hereinafter described. Acid treated sub-bentonites are well known cata-

lysts for the cracking of oil and have been employed as decolorizing and purifying adsorbents in the refining of lubricating oils as produced from crude oils. They have been employed in refining used lubricating oils. They are particularly useful for my process and apparatus. In order, however, to avoid deleterious cracking reaction which may be promoted by such catalysts, I prefer to contact my oil with such catalyst adsorbent at a temperature sufficiently elevated to cause a rapid treatment of the oil, but at a temperature sufficiently low to prevent deleterious cracking. I also restrict my time of contact in the contactor to also assist in minimizing deleterious cracking reactions.

I have also found for the purpose of my process, both in order to produce the desirable treating operation and also to permit of the rapid and simple filtration operation made possible by my apparatus, that it is desirable to employ an adsorbent such as mentioned above, for example, the acid treated sub-bentonites having a close range of particle size, and for this purpose I have found it useful to employ a material of which about 90% to 100% passes through a 100 mesh and containing less than about 20% to 35% of 0 to 20 micron material.

The mixture of oil and clay thus formed is then agitated and pre-oxidized. The oil is heated by closing switch 58, cap 5 being replaced and the closure 21 being removed. Valve 43 is closed. The cap 51 is in place and the spout 34 is closed, as is valve 39. Valve 35 is opened. Water is passed through coils 33 and 44 and into ejector 46. The ejector creates a vacuum in the condenser 30 and contactor 1. Air is drawn through pipes 24 and 25. It bubbles through the oil and clay in contactor 1, agitating them. The air, vapors, and gases discharge through pipe 27, valve 29, into accumulator 30. Any condensable material is collected in 30. Uncondensed gases, vapor and residual air pass through pipe 48 into the ejector 46.

Since the air discharges into the lowermost portion of the mass of oil, a thorough agitation occurs and no sedimentation of the clay is permitted. All portions of the oil are contacted with the clay and subjected to the oxidative influence of the air. As the temperature of the oil rises, the oxidation reaction accelerates. The unstable portion of the oil is adsorbed. The stream of air aided by the vacuum and heat strips the oil of volatile components. Diluent fractions present in the original used oil and any volatile material produced by the pre-oxidation operation are thus removed. The temperature of such pre-oxidation is controlled within the range of about 350° to about 650° F. The thermostat 13 is set to cut out when the temperature rises above the predetermined limit, for instance, 350° to 650° F.

The use of this ejector in the form of a hydro-aspirator, employing as the motive power the stream of cooling water passing through the condenser, permits of a ready and simple means of disposing of the highly objectionable odors which are present in the uncondensed gases. They are entrained in the stream of water passing from the ejector and are disposed of by passing into the sewer. This permits of the use of the apparatus in an enclosed space where otherwise, due to health hazards and the objectionable odor, expensive provisions must be made for the disposing of such vapors. Especially in inhabited

regions, it is not desirable to vent such vapors to the atmosphere, due not only to the pollution of the air, but also to the nuisance character of such vapors.

The use of an ejector in the manner discussed above is thus superior to the use of a vacuum pump for which a stack discharge would have to be provided. Some of the advantages of the ejector may be obtained if the discharge of the mechanical vacuum pump is connected to the sewer, and particularly if the discharge of the pump is connected to the water line from 44 so that the vacuum pump discharges are mixed with water and disposed of by passing to the sewer.

The ejector and also a vacuum pump have the advantage when employed in the manner described above of drawing air for agitation and for oxidation and of assisting in the removal of volatiles and for purging and agitating with steam. It is also possible but not as advantageous to operate the system at superatmospheric pressure by introducing the steam and air under pressure into the reactor and discharging the air and vapors or gases to the atmosphere through 48. In such case the ejector 46 is omitted and the steam generator is operated under pressure and a valve may be provided on 24 to disconnect 20 from 1 and a separate valved connection must be provided to a source of air under pressure to admit air under pressure into 1 through 24.

As stated above the disposal of the air, vapors, gases, and steam from the line 48 to the sewer, particularly in admixture with the water from 44, is a particularly advantageous procedure, and this advantage of the ejector may in part be obtained if the discharge from 48, when employing superatmospheric pressures in the chambers 1 and 30, be passed to the sewer, and particularly if the water from 44 be mixed with this discharge and disposed of by passage to the sewer.

However, the system as described above employing my ejector is believed simpler and to contain advantages set out above which make it superior to the alternative use of a mechanical vacuum pump and particularly to the use of the agitative air or steam operated under pressure and discharging from the unit at atmospheric pressure.

When the contact and pre-oxidation operation is complete, usually in about 10 to 30 minutes, the switch 58 is opened. The water in 20 has been brought to a boil. The cap 21 is placed on the boiler 20 and locked in place. Steam pressure is immediately generated in boiler 20 and steam flows through line 24 and line 25. It bubbles through the oil, keeping the oil agitated and the clay suspended in the oil. Thus there is an immediate substitution of steam for air as an agitating medium and settling of the clay does not occur. The oil and contactor are thus purged of air under the influence of the steam passage aided by the vacuum created by the ejector 46. Valve 29 is closed and valves 43 and 39 are open. Steam accumulates above the oil level and develops pressure. As soon as sufficient pressure is developed, the oil is transferred from the contactor 1 to the cooler 41. Cooler 41 is vented through the pipe 40b, cross 40a, valve 39, into accumulator 30. The check valve 40 prevents the passage of the vapor stream to the atmosphere. The accumulator is vented through 48 and connected to the ejector 46. Water passing out through the ejector assists in sucking out the vapors, air, and steam.

When all of the oil has been transferred, steam passes through pipe 28, line 31, valve 39, and appears in sight-glass 38. The color in the sight-glass changes, indicating the steam is passing through line 37.

The passage of steam through the cooler 41 removes air in the container 41 and thus prevents an oxidation while the oil is at a high temperature. Since, as will be explained more fully below, the clay particles settle from the oil, air oxidation at this point while the oil is at a high temperature and in the presence of a diminished quantity of treating agent, resulting from the partial settling of the clay, would re-introduce unstable components into the oil. The use of steam to transfer the hot oil into the cooler and the exclusion of air from contact with the hot oil has also the advantage of preventing flashing of the oil, particularly when the oil is at above its flash point. This is an important safety factor.

Valve 39 is then closed, valve 43 is closed, and valve 29 is opened. Steam pressure will then be vented through contactor 1, through valve 27, through line 29, into container 30 to be exhausted through line 48. The contactor is thus purged of oil vapor. Caps 5 and 21 may then be removed for a new charge of oil to be processed as previously described. The purging of the contactor prevents flashing of the hot oil vapor when the cap 5 is removed.

The oil in container 41 is cooled by cooling coil 44 and a partial sedimentation of the clay occurs. The oil is cooled to a temperature of below the flash point of the oil, for example, about 300° to 400° F. or lower. The pressure in chamber 41 is measured on gauge 40'. When the temperature is above 212° F. the pressure will be above atmospheric and therefore no air leaks in through check valve 40. As the temperature drops to below 212° F., the oil is sufficiently resistant to oxidation so that no appreciable harm can be done to the oil by contact with air. Valve 50 is opened and the oil containing the partially settled clay drops into chamber 51. A suitable bucket or receptacle is placed under 51 through a door in the closure 19 provided therefor. The clay settles as a pre-coat on the filter 52. An air line is connected to 37 from an air compressor normally available at all garages and service stations. If this is not available, a hand pump may be employed. The oil and clay in 41 are therefore pressured through the filter 51 and when filtration stops the air may then be cut off. Valve 50 is closed and the oil which has been treated in the contactor 1 during the cooling and filtering operation may be now transferred if sufficient contact time has been provided.

The filter is removed by unscrewing the bolt 56. The clamp 55 is swung to one side, the perforated disc 54 is removed and a new filter is replaced and assembled by sealing with clamp and screw 56 and filtration may now be carried out as previously described.

While I have described my apparatus as employing electrical heaters, since they are cheap and convenient, they may be replaced by gas or oil burners, particularly when the apparatus is to be used where electricity is not available.

As a modification of the above apparatus and as a useful aid in the proper carrying out of the process, I may provide a convenient package for the catalyst adsorbent which may also be used as a collector for the filter cake. For this purpose I provide a container 65 of a diameter suitable to be inserted into the container 51 so as to make a snug

but slidable fit. The container is closed by a piece of filter medium 66 such as that mentioned above. This filter medium may be glued or otherwise attached to the wall 65. The ends of the container are covered by a removable bottom and by a removable top. The container contains the proper amount of reagent to be employed for treating the volume of oil to be charged to contactor 1. The top is removed and the contents are poured into the contactor. The empty carton is inserted into the chamber so that the filter medium is adjacent the end of the container 51 at the position occupied by 53 in the previous modification. A gasket is provided to be placed at the wall 51 and to seal the plate 54 against the wall. The filter is otherwise assembled as previously described. When the filtration is completed the filter cake will be formed on the filter medium inside the container 65 and may be readily disposed of by sliding the container from the chamber 51.

While for economy of construction and simplicity of design numerous automatic devices for opening and closing valves, either on a time cycle or by temperature and pressure controls and the use of indicating or recording devices for the various pressures and temperatures employed, are not employed, they may be introduced. Experience has shown that they are not necessary for the economical and safe execution of my process and for the safe and convenient operation of my device.

The apparatus and procedures herein described while particularly useful in treating used lubricating oil may also be employed with advantage in treating other lubricating oils as well as vegetable and animal oil or other oils and materials which are susceptible to treatment by means of granular solids, as, for example, adsorbents or catalysts.

While I have described a particular embodiment of my invention for the purpose of illustration, it should be understood that various modifications and adaptations thereof may be made within the spirit of the invention as set forth in the appended claims.

I claim:

1. An apparatus for treating oil, which comprises a treating chamber, a sealable oil inlet to said chamber, an air and steam inlet to the bottom of said chamber, a vapor outlet from said chamber, a condenser connected to said vapor outlet, a valve in said connection between said treating chamber and said condenser, an oil transfer tube passing through an upper portion of the wall of said treating chamber and extending into and terminating at the lower point of said treating chamber, an oil receiving chamber, a pipe connecting said receiving chamber and said transfer line, a valve in said pipe connection between said oil transfer tube and said oil receiving chamber, a separate air pressure line connected to said receiver, a vapor outlet from said oil receiving chamber, a connection between said vapor outlet and said condenser, a valve in said last-mentioned connection, a vacuum generating means connected to said condenser, a liquid discharge line connected to said receiving chamber, and a filter connected to said discharge line.

2. An apparatus for treating oil which comprises a treating chamber, a sealable oil inlet to said chamber, an air and steam inlet to the bottom of said chamber, a vapor outlet from said chamber, a condenser connected to said vapor outlet, a valve in said connection between said treating chamber and said condenser, an oil transfer tube passing through an upper portion

of the wall of said treating chamber and extending into and terminating at the lower point of said treating chamber, an oil receiving chamber, a pipe connecting said receiving chamber and said transfer tube, a cooling coil in said receiving chamber, a valve in said pipe connection between said oil transfer tube and said oil receiving chamber, a separate air pressure line connected to said receiver, a vapor outlet from said oil receiving chamber, a connection between said vapor outlet and said condenser, a valve in said last-mentioned connection, a vacuum generating means connected to said condenser, a liquid discharge line connected to said receiving chamber, and a filter connected to said discharge line.

3. An apparatus for treating oil, which comprises a treating chamber, a sealable oil inlet to said chamber, an air and steam inlet to the bottom of said chamber, a vapor outlet from said chamber, a condenser, a cooling coil in said condenser, a vapor line connected to said vapor outlet and to said condenser, a valve in said connection between said treating chamber and said condenser, an oil transfer tube passing through an upper portion of the wall of said treating chamber and extending into and terminating at the lower point of said treating chamber, an oil receiving chamber, a pipe connecting said receiving chamber and said transfer tube, a cooling coil in said receiving chamber, a valve in said connection between said oil transfer line and said receiving chamber, a separate air pressure line connected to said receiver, a vapor outlet from said oil receiving chamber, a connection between said vapor outlet and said condenser, a valve in said last-mentioned connection, a water jet connected to said condenser, a water connection between said cooling coils and said water jet, a liquid discharge line to said receiving chamber, and a filter connected to said discharge line.

4. An apparatus for treating oil, which comprises a treating chamber, a sealable oil inlet to said chamber, an air and steam inlet to the bottom of said chamber, a vapor outlet from said chamber, a condenser connected to said vapor outlet, a valve in said connection between said treating chamber and said condenser, an oil transfer tube passing through an upper portion of the wall of said treating chamber and extending into and terminating at the lower point of said treating chamber, an oil receiving chamber, a pipe connecting said receiving chamber and said transfer tube, a valve in said pipe connection between said oil transfer tube and said oil receiving chamber, a separate air pressure line connected to said receiver, a vapor outlet from said oil receiving chamber, a connection between said vapor outlet and said condenser, a sight glass in said pipe, a valve in said last-mentioned connection, a vacuum generating means connected to said condenser, a liquid discharge line to said receiving chamber, and a filter connected to said discharge line.

5. An apparatus for treating oil, which comprises a treating chamber, a sealable oil inlet to said chamber, an air and steam inlet to the bottom of said chamber, a vapor outlet from said chamber, a condenser, a cooling coil in said condenser, a pipe connected to said vapor outlet and to said condenser, a valve in said connection between said treating chamber and said condenser, an oil transfer tube passing through an upper portion of the wall of said treating chamber and extending into and terminating at the lower point of said treating chamber, an oil receiving chamber,

ber, a pipe connecting said receiving chamber and said transfer line, a cooling coil in said receiving chamber, a valve in said connection between said oil transfer tube and said receiving chamber, a separate air pressure line connected to said receiver, a vapor outlet from said oil receiving chamber, a connection between said vapor outlet and said condenser, a sight glass in said pipe, a valve in said last-mentioned connection, a water jet connected to said condenser, a water connection between said cooling coils and said water jet, a liquid discharge line to said receiving chamber, and a filter connected to said discharge line.
